United States Patent Office

Des. 185,832

Patented Aug. 11, 1959

185,832

ILLUMINABLE SIGN

Kenneth W. Barnes, Poland, Ohio

Application March 13, 1958, Serial No. 50,020

Term of patent 14 years

(Cl. D1—12)

The figure is a perspective view of an illuminable sign, showing my new design, the side and rear not shown being substantially like the side and front shown.

The dominant features of my design reside in the full line portions of the drawing.

I claim:

The ornamental design for an illuminable sign, as shown and described.
